UNITED STATES PATENT OFFICE.

JOHN T. GRIFFIN, OF BALTIMORE, MARYLAND.

FLOW-REGULATING DEVICE FOR GAS-BURNERS.

1,388,704.

Specification of Letters Patent. Patented Aug. 23, 1921.

Application filed February 24, 1921. Serial No. 447,603.

To all whom it may concern:

Be it known that I, JOHN T. GRIFFIN, a citizen of the United States, residing at Baltimore, in the county of Baltimore City and State of Maryland, have invented a new and useful Flow-Regulating Device for Gas-Burners, of which the following is a specification.

This invention is a new and useful device for controlling the volume of gas supplied to a gas burner.

One of the objects of the invention is to provide a regulating device for gas burners which will be capable of ready adjustment, and by means of which the volume of gas supplied to a burner may be increased or diminished at will, to maintain the proper proportions of air and gas, irrespective of the pressure in the gas supply main. A further object is to provide a device of the character mentioned, having a regulator tube capable of being connected with any standard burner cock, and having an adjustable discharge orifice. A further object is to provide a stop device mounted on the regulator tube, for maintaining the said tube in any adjusted position with respect to the burner cock, said device permitting of adjustments of the position of the tube to conform to various types of gas burners. A further object is to provide a control means for the regulator tube, the same being adjustably mounted on the stop device, and having means coöperating with the burner, to determine the burner position.

The invention will be hereinafter fully set forth and particularly pointed out in the claims.

In the accompanying drawings:—

Figure 1 is a side elevation illustrating a regulating device constructed in accordance with the invention, in operative position with respect to a gas burner. Fig. 2 is a side elevation of the burner cock with the regulating device attached thereto, the latter being shown in section. Fig. 3 is a sectional view illustrating a slight modification.

Referring to the drawing 10 designates a gas burner of the type commonly employed on gas ranges. It is to be understood however, that this type of burner has been selected solely for illustrative purposes, and that the invention may be applied to any other type of gas burner. The burner cock

11 is of standard construction, provided with a threaded nipple 12, by means of which it may be attached to the gas manifold, and also provided with the usual valve-operating handle 13. At the present time, the manufacturers of gas appliances in the United States have adopted a uniform standard for the style and dimensions of the burner cock, and the drawing conventionally illustrates a device conforming to said standard.

Extending from the burner cock in a direction opposite to that of nipple 12, is a discharge tube 14, provided with an annular shoulder 15, against which the end of the burner normally abuts, thereby determining the burner position with respect to the cock. It is to be understood that the shoulder 15 is a part of the standard construction of the burner cock, but performs no function when the present invention is attached to the latter. Said discharge tube 14 is internally threaded, to receive an exteriorly threaded regulator tube 16, the outer end of which is provided with a discharge orifice 17, and slits 18 leading therefrom, the construction being such as to provide a variable discharge orifice. Adjustably mounted upon the tube 16 is a lock nut 19, which bears against the outer end of the tube 14, and locks the tube 16 against rotation. It is obvious from the drawing, that the distance which the tube 16 protrudes from the tube 14 may be varied, by first loosening the lock nut 19, and then screwing the tube inwardly or outwardly as circumstances may require. The lock nut is provided with suitable means whereby it may be engaged by a tool, for convenient rotation, such as the recesses 19'.

Adjustably mounted on the lock nut 19 is a regulating sleeve 20, internally threaded to engage the threads of said nut. Said regulating sleeve is provided with a projection at its outer end having a discharge orifice 21, and a conical recess 22 contiguous to the latter. Said recess is positioned to engage the split end of the tube 16, for the purpose of compressing said end to reduce the size of the discharge orifice 17. Said sleeve is provided with an annular shoulder 23, which is employed in lieu of the shoulder 15 of the burner cock, to engage the burner, for the purpose of determining the burner position. The sleeve 20 is also provided

with a milled flange 24, by means of which it may be conveniently rotated for adjustments upon the lock nut 19.

In lieu of the split sleeve 16, the construction illustrated in Fig. 3 may be employed. In this form of the invention, the externally threaded regulator tube 16' is employed, the same being closed at its outer end by a tapered valve-like portion 17', having a central bore and lateral openings 18'. The tube 16' may be substituted for the tube 16 in the construction illustrated in Fig. 2, the tapered end 17' coöperating with the orifice 21, to control the amount of gas discharged through said orifice. The regulating sleeve 20' is mounted directly on the tube 16'.

In practice, the regulator tube 16 is engaged with the tube 14 of the burner cock, and adjusted to the proper position to discharge the gas into the burner 10. Said tube 16 is then locked in position by means of the nut 19. The sleeve 20 is engaged with the nut 19, and adjusted thereon until the recess 22 approaches the split end of the tube 16. Then by slight rotating adjustments of the sleeve 20 in one direction, the split end of the tube 16 may be compressed if necessary to reduce the flow of gas or said sleeve may be rotated in the other direction to leave the tube 16 in its normal condition if the full flow of gas is desired.

From the foregoing, it will be readily understood that the invention provides an exceedingly simple device, which may be attached to any standard burner cock, and which may be used in connection with any form of gas burner. It will be particularly noted, that there is sufficient space between the burner cock and the end of the burner, to permit insertion of the fingers to engage the milled flange 24, so that a change of adjustment may be readily made without withdrawing the burner cock and the regulator from the burner, and without necessitating disconnection of the burner cock from the manifold. Thus, if there is any serious change in the gas pressure at the supply main, the regulator may be quickly adjusted to compensate for the change in condition. A further advantage lies in the fact that the regulator device herein described is capable of being applied to installations which are already in use, without necessitating any change in the latter.

Having thus explained the nature of the invention and described an operative manner of constructing and using the same, although without attempting to set forth all of the forms in which it may be made, or all of the forms of its use, what is claimed is:—

1. A gas regulator of the character described comprising a regulator tube having means whereby it may be adjustably con-

nected with a burner cock, means for locking said tube in any adjusted position, and regulating means carried by the locking means for controlling the volume of gas discharged through said regulator tube. 70

2. A gas regulator of the character described comprising a regulator tube having means whereby it may be adjustably connected with a burner cock, means adjustably mounted on the tube for locking it in any 75 adjusted position, and regulating means adjustably mounted on the locking means for controlling the volume of gas discharged through said tube.

3. A gas regulator of the character described comprising an externally threaded regulator tube capable of engaging a correspondingly threaded portion of a burner cock, a lock nut adjustably mounted on said regulator tube, and regulating means carried by the lock nut for controlling the 85 volume of gas discharged through said tube.

4. A gas regulator of the character described comprising a regulator tube having means whereby it may be adjustably connected with a burner cock, means for locking said tube in any adjusted position, and a regulating sleeve adjustably supported by said locking means and having means for controlling the volume of gas discharged 95 through said tube. 90

5. A gas regulator of the character described comprising an externally threaded regulator tube capable of engaging a correspondingly threaded portion of a burner 100 cock, a lock nut adjustably mounted on said regulator tube, and a regulating sleeve adjustably supported by said lock nut and having means for controlling the volume of gas discharged by said regulator tube. 105

6. A gas regulator of the character described comprising a regulator tube having means whereby it may be adjustably connected with a burner cock, said tube having a split end to provide a variable discharge 110 orifice, means for locking said tube in any adjusted position, and regulating means carried by the locking means for varying the size of said discharge orifice. 115

7. A gas regulator of the character described comprising a regulator tube having means whereby it may be adjustably connected with a burner cock, said tube having a split end to provide a variable discharge orifice, means for locking said tube in any 120 adjusted position, and a regulating sleeve adjustably supported by said locking means and provided with means for varying the size of said discharge orifice. 125

8. A gas regulator of the character described comprising an externally threaded regulator tube capable of engaging a correspondingly threaded portion of a burner cock, said tube having a split end to provide a variable discharge orifice, a lock nut 130

mounted on said sleeve, and regulating means carried by said lock nut for varying the size of the discharge orifice.

9. A gas regulator of the character described comprising an externally threaded regulator tube capable of engaging a correspondingly threaded portion of a burner cock, said tube having a split end to provide a variable discharge orifice, a lock nut mounted on said sleeve, and a regulating sleeve adjustably mounted on said lock nut and provided with means for varying the size of said discharge orifice.

10. A gas regulator of the character described comprising an externally threaded regulator tube capable of engaging a correspondingly threaded portion of a burner cock, said tube having a split end to provide a variable discharge orifice, a lock nut mounted on said sleeve, and a regulating sleeve adjustably mounted on said lock nut and provided with a discharge orifice, said sleeve also having a conical recess contiguous to said orifice and positioned to engage the split portion of said regulator tube.

11. A gas regulator of the character described comprising a regulator tube having means whereby it may be adjustably connected with a burner cock, means for locking said tube in any adjusted position, and a regulator sleeve adjustably mounted on said locking means and having a shoulder for determining the burner position.

12. A gas regulator of the character described comprising a regulator tube having means whereby it may be adjustably connected with a burner cock, means for locking said tube in any adjusted position, and a regulating sleeve adjustably supported by said locking means and having means for controlling the volume of gas discharge by said tube, said sleeve having a flange by means of which it may be manually adjusted.

13. A gas regulator of the character described comprising an externally threaded regulator tube capable of engaging a correspondingly threaded portion of a burner

cock, a lock nut adjustably mounted on the threaded portion of said tube, and a regulator sleeve adjustably mounted on said nut and having a discharge orifice, said sleeve also having means complementary to one end of said tube for controlling the volume of gas discharged therefrom.

14. A gas regulator of the character described comprising an externally threaded regulator tube capable of engaging a correspondingly threaded portion of a burner cock, a lock nut adjustably mounted on the threaded portion of said tube, and a regulating sleeve adjustably mounted on said nut and having a discharge orifice, said sleeve having means complementary to one end of said tube for controlling the volume of gas discharged therefrom, said sleeve also having an annular burner positioning shoulder and an actuating flange.

15. A gas regulator of the character described comprising an externally threaded regulator tube capable of adjustably engaging a correspondingly threaded portion of a burner cock, said tube having a split end to provide a variable discharge orifice, a lock nut adjustably mounted on said regulator tube, said nut being exteriorly threaded, and a regulator sleeve internally threaded to adjustably engage said lock nut, said sleeve having a discharge orifice, and a recess contiguous thereto positioned to vary the size of the discharge orifice of said regulator tube, said sleeve also having a burner positioning shoulder and an actuating flange.

16. A gas regulator of the character described comprising an externally threaded regulator tube capable of adjustably engaging a correspondingly threaded portion of a burner cock, and a regulator sleeve adjustably supported by said tube, said tube and said sleeve having complementary means for controlling the volume of gas discharged from said tube.

In testimony whereof I have hereunto set my hand.

JOHN T. GRIFFIN.
